Michael John Tovey, Letchworth, England, assignor to
Herbert Controls and Instruments Limited, Letchworth,
England

Filed June 6, 1972, Ser. No. 260,346

Claims priority, application Great Britain Dec. 7, 1972

Term of patent 14 years

Int. Cl. D10—04

U.S. Cl. D52—6 R

FIG. 1

FIG. 2

FIG.3

FIG. 4

FIG. 5

FIG. 1 is a perspective view taken from the front and one side of a display instrument for measured information, showing my new design;

FIG. 2 is a perspective view taken from the rear and one side thereof;

FIG. 3 is a side elevational view thereof;

FIG. 4 is a top plan view thereof; and

FIG. 5 is a bottom plan view thereof.

I claim:

The ornamental design for a display instrument for measured information, substantially as shown.
